UNITED STATES. PATENT OFFICE.

HERBERT T. HERR, OF MERION, PENNSYLVANIA, ASSIGNOR TO WESTINGHOUSE ELECTRIC AND MANUFACTURING COMPANY, A CORPORATION OF PENNSYLVANIA.

TURBINE.

Application filed October 11, 1920, Serial No. 416,094. Renewed February 24, 1923.

To all whom it may concern:

Be it known that I, HERBERT T. HERR, a citizen of the United States, and a resident of Merion, in the county of Delaware and State of Pennsylvania, have invented a new and useful Improvement in Turbines, of which the following is a specification.

This invention relates to power developing apparatus and more particularly to organized turbine structures including two or more power-developing elements in which one or more elements at times are employed in developing power, while the others are inoperative or running idle.

An object of the invention is to produce a new and improved power system or organized turbine apparatus which is highly efficient under ordinary operating conditions and in which are provided both ahead and astern elements which are located in a single casing and which are adapted to operate independently.

A further object is to provide, in a turbine having ahead and astern sections in which one section is idle while the other is in operation, a cooling means for the idle section.

In the drawing, Fig. 1 is a diagrammatical representation of a turbine structure embodying one form of my invention and Fig. 2 is a diagrammatical representation of a modification thereof.

In turbines of the type comprising reversing elements exhausting into a main exhaust chamber, a considerable quantity of steam is drawn into the idle, rotating ahead element when the steam is being delivered to the astern elements. This steam is churned and agitated by the rotation of the blades of the idle elements and often develops heat to such a degree as to cause injury to the casing, drum and blades of the idle sections. By my invention I prevent this heating of the idle sections, due to the churning of the steam, by providing means for withdrawing steam from near the normal inlet end of the idle elements, and thus causing a slow stream of relatively cool exhaust steam to flow constantly through the idle sections, maintaining therein safe working temperatures.

The construction illustrated in Fig. 1, in which the ahead and astern elements of a turbine are similar in structure, equal in capacity and arranged symmetrically to a

central exhaust, is particularly adapted for power systems in which a reverse movement of the motor is required during relatively long periods, and high efficiency of the motor during such reverse rotation is desired, as for example, in the operation of ferry boats. This construction comprises a turbine casing 10 and a drum 11, axially and rotatably mounted within the casing. The ahead elements comprise a high-pressure impulse section 12 and a low-pressure reaction section 13. Similarly, the astern elements comprise a high-pressure impulse section 14, and a low-pressure reaction section 15. The leaving blades of both the sections 14 and 15 discharge into a central exhaust chamber 16.

Communicating with the interior of the casing between the impulse section 12 and the reaction section 13 is a by-pass pipe 17 which communicates at its outer end with a centrally disposed pipe 18, the latter opening into the exhaust chamber 16 of the turbine. A similar by-pass 19 communicates at one end with the interior of the casing between the impulse section 14 and the reaction section 15 and at the other end with the centrally disposed pipe 18. A steam main 20 provided with a valve 21 supplies steam to the nozzles 22 arranged in operative relation to the blades of the impulse section 12. A similar main 23, equipped with a valve 24 supplies steam to the nozzles 25 of the impulse section 14. Pressure-operated valves 26 and 27 are provided in each of the by-pass pipes 17 and 19. Mounted upon the casing of valve 26 is a cylinder 28 in which a piston 29 is arranged to reciprocate. A valve stem 30 rigidly connects the valve 26 and piston 29, and a spring 31 positioned in the cylinder 28 holds the valve 26 to its seat. The valve 27 is in the same way equipped with an operating mechanism comprising a cylinder 32, and a piston 33, connected to the valve 27 by a valve stem 34 and retained upon its seat by a spring 35. A pipe 36 connects the steam main 23 at a point between the valve 24 and the nozzles 25 with the chamber formed in cylinder 28 beneath the piston 29. A pipe 37 likewise connects the steam main 20 at a point between the valve 21 and the nozzles 22 with the chamber formed in the cylinder 32 beneath the piston 33.

If desired, an ejector may be positioned

- centrally above the pipe 18 for facilitating the withdrawal of steam from the by-pass pipes 17 and 19. This ejector may be supplied with steam from the mains 20 and 23 by means of conduits 39 and 40, in each of which is preferably placed a check valve 41 and 42. These conduits 39 and 40 may be further equipped with manually controlled valves 43 and 44.
- Having thus described a structure embodying my invention, the operation is as follows: Assuming that the valve 21 is open and the valve 24 closed, steam is admitted from the main 20 to the sections 12 and 13 and is discharged into the exhaust chamber 16. The rotation of the idle blades in the sections 15 draws in steam from the exhaust chamber, which, if allowed to remain there, would cause excessive heating due to the agitation of the steam in this portion of the turbine. This steam in the idle section 15 is, however, withdrawn through the by-pass 19, since upon opening the valve 21, steam from the main 20 traverses the pipe 37 and enters the cylinder 32 beneath the piston 33, forcing the piston upwardly and opening the valve 27. This places the inlet end of the sections 15 in communication with the exhaust chamber 16 and thereby produces a cooling of the idle sections by the slow reverse flow of steam through these sections. The flow of steam through, and hence the cooling action in, the idle sections may be increased by the operation of the ejector 38, which receives its motive fluid from the main 20 through the pipe 39. The check valve 42 prevents a reverse flow of steam through the pipe 40. In reversing the turbine, the valve 21 is closed and the valve 24 is opened. The valve 27 automatically closes, the valve 26 automatically opens and the cooling mechanism operates with relation to the idle section 13 in a like manner to that described above.
- In Fig. 2 is illustrated a turbine in which the reversing elements comprise a single impulse section 14 which is adapted for use where a high efficiency in the reverse operation of the turbine is not of great importance, as in motors where a reverse rotation is desired only for relatively short periods. The structure, in the main, is the same as that described and illustrated in relation to Fig. 1. Like parts in both figures have been designated by the same reference numbers and a detailed description of the structure need not be here repeated. It should be noted that but a single by-pass element 17 is employed in this form of my invention. The pipe 18 leads to the exhaust chamber 16 adjacent the condenser connection. The steam for operating the ejector 38 is supplied by a pipe 39 which communicates with the pipe 36. In running astern, the operation of the cooling means for the idle sec-

tions 13 is identical with that described above with relation to the construction illustrated in Fig. 1. In running ahead, no provision need be made for cooling the astern impulse section, since it is located substantially in the exhaust chamber and is subjected to the flow of exhaust steam on its way to the condenser.

It is to be understood that the ahead and astern valves 21 and 24 are essentially maneuvering valves and that the turbine should also be equipped with a separate inlet valve, such as valve 48 in Fig. 2, capable of being controlled by a governor for the purpose of preventing racing.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:—

1. In an apparatus of the character described comprising an ahead turbine element, an astern turbine element, each of said elements arranged to run idly while the other is developing power, an exhaust chamber into which both turbine elements exhaust, a by-pass pipe connecting an inlet portion of said ahead turbine element with the exhaust chamber, a valve in said by-pass and means controlled by the pressure in the supply pipe of the astern turbine element for opening said valve.

2. In an apparatus of the character described comprising a casing, an ahead turbine element and an astern turbine element in said casing, steam supply pipes for said elements, valves in said supply pipes, an exhaust chamber into which both turbine elements exhaust, by-pass connections leading from an initial stage of each of the turbine elements to the exhaust chamber, a valve in each by-pass connection, and means controlled by the pressure in the supply pipe of one turbine element for opening the valve in the other turbine by-pass connection.

3. In an apparatus of the character described comprising an ahead turbine element, an astern turbine element, each of said elements arranged to run idly while the other is developing power, an exhaust chamber into which both turbine elements exhaust, a by-pass pipe connecting an initial stage of said ahead turbine element with the exhaust chamber, and means operative while the astern turbine is developing power for opening said by-pass connection.

4. In an apparatus of the character described, a casing, a turbine element arranged to run idly while not developing power, an

5 ejector, a conduit connecting an initial stage of the turbine element to said ejector, a steam supply for said ejector and means for rendering operative said ejector when the turbine element is rotating without developing power.

6 5. In an apparatus of the character described, comprising an ahead turbine element, an astern turbine element, each of said 10 elements being arranged to run idly while the other is developing power, a common exhaust chamber for the turbine elements, an 15 ejector discharging into the exhaust chamber, a by-pass pipe connecting an initial stage of the 20 ahead turbine element with said ejector, a valve in the by-pass pipe, means controlled by the pressure in the supply for the astern turbine element for opening said valve, and a steam supply pipe connecting the 25 ejector with said astern turbine supply, whereby when the astern turbine element is developing power, an initial stage of the ahead turbine element will be in communication with the ejector through the by-pass pipe and motive fluid will be supplied the 30 ejector to draw steam through the working passages of the idle ahead turbine element.

35 6. In a multi-stage turbine, the combination of an exhaust chamber, a conduit for connecting a high-pressure stage of the turbine to the exhaust chamber, and a pumping device associated with the conduit to insure flow therethrough from the high-pressure stage to the exhaust chamber.

40 7. In a multi-stage turbine, the combination of an exhaust chamber, a conduit for connecting a high-pressure stage of the turbine to the exhaust chamber, and an ejector in the conduit having its discharge end disposed toward the exhaust chamber.

8. In a turbine having a casing, a rotor,

45 and blading carried by the casing and by the rotor, the combination of means for rotating the rotor other than by said blading, an exhaust chamber for said blading, a conduit for connecting the high-pressure end of the turbine to said exhaust chamber, a pumping device for insuring flow in the conduit from the high-pressure end of the turbine to the exhaust chamber, and means for rendering the pumping device operative dependent upon the operation of the first-mentioned means.

50 9. In a multi-stage turbine having ahead and reversing sections, the combination of an exhaust chamber for the ahead section, a conduit for connecting a high-pressure stage of the ahead section with the exhaust chamber, and a pumping device associated with the conduit to insure flow from said high-pressure stage to the exhaust chamber when the reversing section is in operation.

55 10. In a multi-stage turbine having ahead and reversing sections, the combination of an exhaust chamber for the sections arranged therebetween, a conduit for connecting a high-pressure stage of the ahead section with the exhaust chamber, and a pumping device associated with the conduit to insure flow from said high-pressure stage to the exhaust chamber when the reversing section is in operation.

60 11. In a multi-stage turbine having ahead and reversing sections, the combination of an exhaust chamber for the ahead section, a 70 conduit for connecting a high-pressure stage of the ahead section with the exhaust chamber, and an ejector in the conduit to insure flow from said high-pressure stage to the exhaust chamber when the reversing section is in operation.
